UNITED STATES PATENT OFFICE.

FRANK MANDLER AND EDWARD KOVORIK, OF DELMONT, PENNSYLVANIA.

WRENCH.

1,098,161.

Specification of Letters Patent.

Patented May 26, 1914.

Application filed December 28, 1912. Serial No. 739,016.

To all whom it may concern:

Be it known that we, FRANK MANDLER and EDWARD KOVORIK, citizens of the United States of America, residing at Delmont, in the county of Westmoreland and State of Pennsylvania, have invented certain new and useful Improvements in Wrenches, of which the following is a specification, reference being had therein to the accompanying drawing.

This invention relates to wrenches, and more particularly to that type of wrench ordinarily used for rotating nuts and bodies having flat facets.

The primary object of our invention is to provide, in a manner as hereinafter set forth, a quick acting nut wrench means to coöperate with the movable jaw thereof in holding the jaw in adjusted position.

With the above and other objects in view the invention resides in the novel construction, combination and arrangement of parts to be hereinafter specifically described and then claimed.

Reference will now be had to the drawing, wherein:—

Figure 1 is a side elevation of a wrench in accordance with this invention, Fig. 2 is a longitudinal sectional view of the same, showing certain parts thereof in adjusted positions in dotted lines, Fig. 3 is a perspective view of a detached gripping member, Fig. 4 is a perspective view of a detached locking pawl, Fig. 5 is a similar view of a detached locking cam, and Fig. 6 is a longitudinal sectional view of a portion of the wrench showing one of the tools thereof in an active position.

Further describing our invention in detail with reference to the accompanying drawing, wherein like numerals denote corresponding parts throughout: 1 denotes a shank, rectangular in cross section, said shank having the outer end thereof provided with a fixed or integral jaw 2 having a flat gripping surface 3 extending at right angles to the front side of the shank 1. The inner end of the shank 1 is reduced and terminates in a cylindrical stem 4, said stem having a longitudinal cylindrical pocket 5 with the inner end thereof exteriorly screw threaded, as at 6.

7 denotes a longitudinal groove formed in the front side of the shank 1, said groove being in communication with an opening 8 formed in the jaw 2. The groove 7 termi-

nates in proximity to the reduced end or stem 4 of the shank and the inner end of said groove is in communication with a recess 9. The rear wall of the groove has two recesses 10 and 11, the purpose of which will presently appear.

12 denotes a rack or toothed bar located within the groove 7 and said bar has the front side thereof provided with teeth 13. 60 The outer end of the bar terminates in a screw driver or chisel head 14 and the inner end of said bar is cylindrical, as at 15 to extend into the recess 9. The inner end of the bar 12 has an angle slot 16 in which is located a spring pressed angle locking member 17 that is pivotally mounted upon a transverse pin 18, carried by the bar 12. One end of the member 17 is exposed at the front side of the bar whereby it can be 70 pressed by the finger to remove the opposite headed end 19 out of the recess 10 of the shank 1. The headed end 19 of said member is held normally in the recess 10 by a coiled compression spring 20 located within 80 the slot 16. By shifting the rack bar 12 after the headed end 19 of the member 17 has been shifted out of the recess 10, the screw driver or chisel head 14 of the rack bar protrudes from the jaw 2 and said bar 85 can be locked in an extended position by the headed end 19 of the member 17 engaging in the recess 11. The wrench can therefore be used as a screw driver or chisel.

21 denotes an adjustable jaw slidably 90 mounted upon the shank 1 and having straps 22 embracing said shank. The jaw 21 presents a flat gripping surface 23 at right angles to the shank 1 and confronting the flat gripping surface 3 of the jaw 2. The 95 front side of the adjustable jaw 21 has a large slot or recess 24 and pivotally mounted in said recess by a transverse pin 25 is a gripping member 26 having transverse teeth 27 normally held in engagement with the 100 teeth 13 of the rack bar 12. Easy access is had to the recess 24 through the medium of a detachable side plate 28 and this side plate, in some instances, can be made integral with the adjustable jaw 21.

The gripping member 26 is slotted, as at 29 and pivotally mounted in said slot, by a transverse pin 30 is a locking pawl 31 that engages the gripping member 26. The locking pawl 31 is held normally in engagement 110 with the gripping member 26 by a coiled compression spring 32, one convolution of

said spring engaging the pawl and the other convolution being seated in the gripping member 26.

33 denotes a cam member pivotally mounted in the recess 24 by a transverse pin 34. The cam member has a lever 35 provided with a cross head 36 and this cross head can be seated in a transverse groove 37 provided therefor in the front side of the adjustable jaw 21.

38 denotes a coiled compression spring arranged within the recess 24 and seated in the gripping member 26, said spring shifting the gripping member out of engagement with the rack bar 12, when the locking pawl 31 is shifted, as will presently appear.

39 denotes a tubular handle arranged upon the reduced end or stem 4 of the shank 1, said handle having the inner end thereof provided with a nut or cap 40 that is interiorly screw threaded to screw upon the exteriorly screw threaded end of the stem 4. The threaded bore of the nut 40 is longitudinally slotted, as at 41, and said slot receives a lug 42, of a collar 43, carried by a tool 44 arranged within the pocket 5 of the stem 4. The tool 44 can be in the form of a punch or auger and said tool is retained therein by a tubular headed screw 45 screwed into the nut 40 against the collar 43. The tool 44 can be of special construction, as shown in Fig. 6 and to place the tool in use it is only necessary to remove the screw 45, withdraw the tool, invert the same, again place it in position and return the screw 45 to its ordinary position. When the tool is not in use it is housed within the stem 4 and as the stem is housed within the handle 39, the tool cannot interfere with the use of the wrench or the use of the rack bar 12 as a screwdriver or for other purposes.

To adjust the jaw 21 the cross head 36 is shifted out of the groove 37 after which the

locking lever is swung outwardly whereby the cam 33 is shifted out of engagement with the gripping member 26, as shown by dotted lines in Fig. 2, and consequently out of engagement with the pawl 31. With the cam in this position the jaw 21 can be shifted toward the fixed jaw 2 to engage the facets of a nut or other structure. After the jaw 21 has been firmly adjusted the cam 33 can be restored to its normal position to retain the gripping member 26 in engagement with the rack bar 12, which is nondisplaceable relatively to the shank 1, except when manually adjusted.

While in the drawing there is illustrated a preferred embodiment of our invention, it is to be understood that the structural elements are susceptible to such modifications and variations as fall within the scope of the appended claim.

What we claim is:—

A wrench of the type described comprising a shank, a jaw fixed to the outer end thereof, a rack bar mounted in said shank, a jaw adjustably mounted in said shank, a gripping member located within said jaw and engaging said rack bar, a spring pressed pivoted locking pawl carried by the adjustable jaw and normally engaging said gripping member, a shiftable cam carried by said jaw and engaging said gripping member, and a locking lever carried by said cam and provided with means engaging said pawl whereby the latter is locked to maintain said gripping member engaging with said pawl.

In testimony whereof we affix our signatures in the presence of two witnesses.

FRANK MANDLER.
EDWARD KOVORIK.
